(57) **CLAIM**

The ornamental design for a launching device, as shown and described.

DESCRIPTION

FIG. 1 is a front, top, right side perspective view of the launching device of present invention.

FIG. 2 is a front, bottom, right side perspective view thereof.

FIG. 3 is a top plan view thereof.

FIG. 4 is a bottom plan view thereof.

FIG. 5 is a front elevation view thereof.

FIG. 6 is a rear elevation view thereof.

FIG. 7 is right side elevation view thereof; and,

FIG. 8 is a left side elevation view thereof.

The dash-dash lines indicate portions which form no part of the claimed design. Surface shading lines are included to illustrate contour only and form no part of the claimed design. Portions not illustrated herein form no part of the claimed design.

1 Claim, 8 Drawing Sheets
